UNITED STATES PATENT OFFICE.

CARL OBERLANDER, OF ARASTRA, COLORADO.

WINDMILL-POWER.

SPECIFICATION forming part of Letters Patent No. 691,168, dated January 14, 1902.

Application filed September 12, 1901. Serial No. 75,176. (No model.)

To all whom it may concern:

Be it known that I, CARL OBERLANDER, a citizen of the United States, and a resident of Arastra, in the county of San Juan and State 5 of Colorado, have invented a new and Improved Windmill-Power, of which the following is a full, clear, and exact description.

This invention relates to improvements in windmill power or mechanism; and the object is to provide a power of this description that may be quickly thrown into and out of operative position and in the operation of which there will be no lost motion.

I will describe a windmill-power embodying 15 my invention, and then point out the novel features in the appended claims.

Reference is to be had to the accompanying drawings, forming a part of this specification, in which similar characters of reference indicate corresponding parts in all the figures.

Figure 1 is a sectional elevation of a windmill-power embodying my invention. Fig. 2 is a vertical section at right angles to Fig. 1 and on the line 2 2 of Fig. 3. Fig. 3 is a top 25 plan view, and Fig. 4 is a plan view partly in section.

Referring to the drawings, 5 designates the tower of the usual construction, and mounted on the tower is the turn-table 6. The wind-wheel 7 is mounted on a shaft 8, having bearings in boxes secured to the turn-table, and arranged in the shaft 8 are the cranks 9 and 10. From the crank 9 a link 11 extends to a connection with a cross-head 12, arranged to 30 slide in guides 13, extended upward from the turn-table, and this cross-head is connected to a tubular operating-rod 14, which has a bearing in a sleeve 15, attached to the turn-table. Extended from a pin on the lower end 35 of the operating-rod 14 is a link 16, which at the lower end engages with the crank 17 of a crank-shaft 18, from which power is imparted to machinery to be driven. This shaft 18 has bearings in cross-bars attached to the tower, 40 and on the shaft is a sprocket-wheel 19, having a chain engagement 20 with a sprocket-wheel 21 on a counter-shaft 22, provided with a band-wheel 23. From the crank 10 of the shaft 8 a link 24 extends to and is connected 45 with the pin on a cross-head 25, moving in the guides 13 and connected to a supplemental power-rod 26, which is movable through the

tubular rod 14, and connected to the lower end of the rod 26 is a cross-head 27, from which a link 28 extends to a connection with a crank 29 on the shaft 18. The cranks 17 and 29 are arranged in opposite directions, as are also the cranks 9 and 10, and therefore it is obvious when the shaft 8 is rotated the rods 14 and 26 will be operated in opposite directions 50 for alternately operating the driving-shaft 18, and therefore lost motion is overcome.

I will now describe a means for throwing the wheel into and out of the wind. Mounted to swing horizontally with relation to the 55 turn-table is a frame 30, forming a portion of the vane-rod. The lower member of this frame 30 has pivotal connection with the turn-table, while the upper member of the frame has pivotal connection with a standard 31 on 60 the turn-table. At one side the frame 30 has toggle-link connections 32 33 with the turn-table, the links being connected by a pivot 32^a, and at the opposite side it has toggle-link connections 34 35 with the turn-table, 65 the said links being pivoted together at 35^a. The links 32 and 34 engage with the same pivot 34^a on the frame 30. The inner end of the link 35 is connected to a rock-shaft 36, having bearings in boxes secured to the standard 31, and the upper end of this rock-shaft 70 36 has link connections with the operating-rod 26. As here shown, a lever 37 is rigidly connected to the upper end of the shaft 36, and from this lever 37 a link 38 extends to an 75 arm 39, which connects with the rod 26. The rod 26 is designed to be rotated by a movement of the arm 39; but said rod is also designed to move vertically through said arm. To permit these movements, the rod at its 80 portion passing through the arm is made angular in cross-section. The lower portion of the rod 26 is designed to rotate in the cross-head 27. It is provided with an annular channel, into which pins attached to the cross-head extend, as clearly shown in Fig. 1. Below the cross-head 27 the said rod 26 is made angular in cross-section and engages in the hub portion of a miter-gear 40, which is supported in a cross-bar 41, attached to the tower. 85 The miter-gear 40 meshes with a miter-gear 42 on a shaft 43, attached to the outer end of which is a sprocket-wheel 44, having a chain connection 45 with a sprocket-wheel 46, at

tached to a shaft 47 at the base of the tower. On this shaft 47 is a hand-wheel 48. By rotating the shaft 47 the vane may be thrown into and out of the wind—that is, by rotating 5 the said shaft in one direction the chain-gearing and the miter-gearing will rotate the rod 26, which through the link connections will rock the rock-shaft 36, and consequently move the frame 30, carrying the vane to operative 10 position, as indicated in Fig. 3. By rotating the shaft 47 in the opposite direction the frame carrying the vane will be moved to the position indicated in Fig. 4, and thus carry the wind-wheel out of operative position.

15 To prevent undue shock or strain, the links 32 33 are connected to the links 34 35 by means of a spring 49, and to limit the movement of the frame toward its inoperative position a stop-finger 50, attached to the link 32, is designed to engage with an angle-arm 51, attached to the rock-shaft 36, and a pin extends from the link 35 into a slot in said angle-arm 51.

Having thus described my invention, I 25 claim as new and desire to secure by Letters Patent—

1. In a windmill-power, a tower, a turn-table on the tower, a windmill-shaft mounted on the turn-table and having two cranks, a 30 tubular operating-rod having connection with one of the cranks, a supplemental operating-rod extended through the tubular rod and having connection with the other crank, a double crank-shaft with which the lower ends 35 of said rods connect, a vane-carrying frame mounted to swing, and connections between said frame and the supplemental rod, whereby the frame may be swung substantially as specified.

40 2. In a windmill-power, a tower, a turn-table on the tower, a wheel-shaft supported on the turn-table and having two cranks, operating-rods connecting with said cranks, one of said rods having a rotary motion, means 45 operated from the base of the tower for causing said rotary motion, a vane-carrying frame mounted to swing relatively to the turn-table, and connections between said frame and the said rotary shaft, whereby the frame may be 50 turned or deflected, substantially as specified.

3. In a windmill-power, a tower, a turn-table

on the tower, a double crank-shaft mounted on the turn-table, a tubular operating-shaft movable through the turn-table, a link connection between said tubular shaft and one of 55 the cranks of the crank-shaft, an auxiliary operating-rod movable through the tubular rod, a link connection between said auxiliary rod and the other crank of the crank-shaft, a crank-shaft supported in the tower below the 60 turn-table, connections between the operating-rods and the cranks of said last-named crank-shaft, a counter-shaft supported in the tower, and driving connections between the last-named crank-shaft and said counter-shaft, substantially as specified.

4. In a windmill-power, a tower, a wind-wheel shaft supported on the tower, an operating-rod having connection with said shaft, a vane-carrying frame mounted to swing horizontally with relation to the tower, a vertical 70 rock-shaft, link connections between the upper end of said rock-shaft and the operating-rod, link connections between said rock-shaft and the vane-carrying frame, and link connections between said vane-carrying frame and the turn-table on the tower, substantially as specified.

5. In a windmill-power, a tower, a turn-table on the tower, a wind-wheel shaft supported 80 on the turn-table, operating-rods having connection with said shaft, one rod being movable in the other, a vane-carrying frame mounted to swing on a horizontal plane, a vertical rock-shaft, an arm extended from the inner 85 of said operating-rods and through which said rod is movable, link connections between said arm and the rock-shaft, link connections between said rock-shaft and the vane-carrying frame, link connections at the opposite side 90 between said frame and the turn-table, a spring connecting the opposite links, a stop-finger carried by a link of one side, and an angular stop-arm attached to the rock-shaft, substantially as specified.

95 In testimony whereof I have signed my name to this specification in the presence of two subscribing witnesses.

CARL OBERLANDER.
